Patented Dec. 5, 1922.

UNITED STATES PATENT OFFICE.

WILLIAM H. FRASER, OF NEW YORK, N. Y.

DOUCHE.

Application filed February 19, 1920; Serial No. 359,990. Renewed April 18, 1922. Serial No. 555,228.

To all whom it may concern:

Be it known that I, WILLIAM H. FRASER, a citizen of the United States, and a resident of New York, in the county of New York 5 and State of New York, have invented certain new and useful Improvements in Douches, of which the following is a specification.

The present invention relates to improvements in douches, that is to say to devices 10 for irrigating and cleaning certain parts of the body, such as for instance the mouth cavity, nasal passages, etc.

The main object of the invention is to provide 15 a device of this type, whereby a medicated liquid is supplied under pressure, preferably derived from a water faucet, to the parts to be cleaned.

Another object of the invention is to produce 20 a douche of the character mentioned which is simple in construction, efficient in operation and one which may be conveniently handled.

With these and other objects in view, 25 which will more fully appear as the nature of the invention is better understood, the same consists in the combination, arrangement and construction of parts hereinafter described, pointed out in the appended claim 30 and illustrated in the accompanying drawings, it being understood that many changes may be made in the size and proportion of the several parts and details of construction within the scope of the appended claim, 35 without departing from the spirit or sacrificing any of the advantages of the invention.

One of the many possible embodiments 40 of the invention is illustrated in the accompanying drawings, in which:—

Figure 1 is a side elevation, partly in section, of a douche constructed in accordance with the present invention; and Fig. 2 is a section taken on line 2—2 of Fig. 1.

In the drawings, the numeral 10 indicates 45 a chambered body, mounted upon a handle 11. The chamber 12 of the body 10 is provided with an inlet opening 13, in communication with a tube 14, the latter leading through the handle 11 and having a 50 nipple 15, with which is engaged one end of a, preferably, flexible hose 16, the other

end of which is adapted to be connected with a water faucet. The chamber 12 is furthermore provided with a discharge opening 17, 55 to which is connected a nozzle 18, the free end of which is provided with a plurality of perforations 19. This nozzle is adapted to be inserted into the cavity to be irrigated and cleaned. 60

Upon the chambered body 10 is mounted a receptacle 20, having a filling opening 21, that is normally closed by a cap 22. The receptacle communicates with the chamber 12, the communication being controlled by 65 a valve 23, for instance a poppet valve, upon the stem of which is coiled a spring 24, tending to hold the valve upon its seat. The outer end of the valve is provided with a head 25, against which bears a shiftable 70 member 26, that is mounted on guides 27 on the body 10. This shiftable member is provided with a finger piece 28, projecting below the chambered body 10. 75

In use, a medicated liquid, for instance an antiseptic solution, is placed into the receptacle 20 and the hose 16 attached to a water faucet. The nozzle 19 is inserted into the cavity to be cleaned, and the faucet turned to open position. The operator 80 forces the finger piece 28 toward the handle 11, whereby the valve 23 is unseated and a quantity of medicated liquid flows into the chamber, where it mingles with the water passing through the same and is carried 85 under pressure into the cavity to be cleaned. The quantity of medicated liquid flowing into the chamber is within the control of the operator, it depending entirely upon the time interval during which the valve is kept 90 from its seat. When the finger piece 28 is released, the spring 24 seats the valve, thereby stopping the flow of medicated liquid into the chamber 12.

The nozzle 18 is detachable from the 95 chambered body and may be replaced by others of varying sizes, according to the requirements.

What I claim is:—

In a device of the character described, 100 the combination with a chambered body having an inlet opening and a discharge opening, a handle supporting said chambered body, a tube passing through said

handle communicating with said inlet opening, a nozzle attached to said chambered body communicating with said discharge opening, a closed receptacle mounted upon 5 and adapted to communicate with the chamber in said body, a valve for controlling the communication between said chamber and

said receptacle, and means projecting below said chambered body and mounted adjacent said handle for operating said valve.

Signed at New York, in the county of New York and State of New York, this 29th day of December, 1919.

WILLIAM H. FRASER.
